UNITED STATES PATENT OFFICE.

KATHARINE A. MCINTIRE, OF RICHMOND, VIRGINIA.

ATTACHMENT FOR SLIPPERS

No. 884,520.

Specification of Letters Patent.

Patented April 14, 1908.

Application filed January 27, 1908. Serial No. 412,910.

To all whom it may concern:

Be it known that I, KATHARINE A. MCINTIRE, a citizen of the United States, residing at Richmond, in the county of Henrico and State of Virginia, have invented an Attachment for Slippers, of which the following is a full and complete specification.

The primary object of my invention is to provide a simple and inexpensive device which may be readily attached to a slipper or other low-quartered shoe and will embrace the heel of the foot of the wearer and will hold the heel portion of the slipper or shoe closely on the foot.

With this principal object in view the invention contemplates the provision of a spring clip comprising an attaching plate and opposite spring members of different lengths terminating in inclined engaging fingers, whereby the attaching plate will fit within the shoe at the heel portion thereof and dispose the spring members so that they will embrace and lightly clamp the narrowed portion of the heel of the foot below the ankle bones, all as hereinafter fully described and claimed.

In the accompanying drawings, which form a part of this specification: Figure 1 is a side view illustrating the application of my invention, the rear part of the slipper being broken away to expose the spring clip. Fig. 2 is a transverse sectional view through the slipper and holding clip. Fig. 3 is a detail perspective view of the spring-clip.

Like numerals of reference indicate like parts in the several figures of the drawings.

In carrying out my invention I make up the clip of a single piece of spring metal shaped to provide an attaching plate 5, and at opposite sides of the plate upwardly-projecting curved members 6 terminating at their ends in laterally projecting inclined portions or fingers 7, which latter are slightly curved, for the purpose hereinafter stated.

In forming the device the attaching plate 5 thereof is of a shape and size corresponding approximately with the heel portion of the inner sole of the slipper or shoe, that is to say curved at the rear end and having the sides slightly converging from that end, so that said heel portion of the inner sole will lie directly upon this plate. The spring members 6 are curved outwardly and inwardly so as to conform approximately to the lower part of the heel of a foot and are of different lengths to conform to the difference

in height of the inner and outer ankle bones, and the terminal laterally projecting portions or fingers 7 are curved slightly, as shown, so as to conform to that part of the foot immediately below the ankle bones at the narrowest portion of the heel.

In attaching the device the heel portion of the inner sole of the slipper or shoe is lifted up and the device placed within the slipper so that the attaching plate 5 will rest upon the bottom thereof directly above the heel, and is secured by nails or screws which pass through holes 9 in said plate. The inner sole is then replaced lying over the attaching plate of the device, and the spring members 6 will then be disposed near the opposite sides of the upper so that the heel of the foot will pass between said members as it enters the slipper or shoe.

It will be understood that the spring members of the clip are of thin metal and therefore do not grip the heel with such force as to be uncomfortable to the wearer, the engagement being only sufficient to hold the heel portion of the slipper or shoe up against the foot in walking. It will be noted, also, that by providing a thin attaching plate which is of the same size as the heel portion of the inner sole, and placing it under the latter, a smooth unbroken surface will be provided for the heel of the foot to rest upon.

The devices will be made of sizes to be attached to slippers or low-quartered shoes of the conventional styles, and may be applied in making the slippers or shoes or sold as a separate article to be attached by the purchaser or by the dealer.

Having thus described my invention, what I claim as new, and desire to secure by Letters Patent, is:—

1. An attachment for slippers or shoes, comprising a heel-shaped attaching plate and upwardly-projecting spring members of different lengths located at the opposite edges thereof and curved to conform to the heel of the foot, said upwardly-projecting members terminating in heel engaging portions, substantially as shown and described.

2. An attachment for slippers or shoes, comprising an attaching plate adapted to fit within and substantially conform to the heel portion of the slipper or shoe, spring members of different lengths projecting upwardly from the side edges of the attaching plate and curved to conform to the lower portion of the heel of the foot, and laterally

projecting fingers at the opposite sides of the upper ends of the spring members, said fingers being inclined and adapted to engage the heel below the ankle-bone, substantially as herein shown and described.

3. In combination with a slipper or shoe, an attachment therefor comprising an attaching plate of the same size as the heel portion of the inner sole and provided with holes 10 for the attaching means, spring members projecting upwardly at the opposite side edges of the attaching plate and curved to conform to the lower portion of the heel of the foot, and laterally projecting curved portion 15 or fingers at the upper ends of said spring members and adapted to engage the sides of the foot below the ankle, the attaching plate of the device being disposed under the inner sole.
- 20 4. In combination with a slipper or shoe including the inner sole thereof, of an attachment comprising an attaching plate of the

same size as the heel portion of the inner sole and provided with holes for the attaching means, spring members of different 25 lengths projecting upwardly at the opposite side edges of the attaching plate and each curved to correspond to the opposite sides of the heel of the foot and to extend to a point below the ankle bone, respectively, and laterally projecting curved portions or fingers 30 at the upper ends of the spring members adapted to engage the sides of the foot immediately below the ankle, the attaching plate being disposed under the inner sole of the 35 shoe, as herein shown and for the purposes set forth.

In testimony whereof I have signed my name to this specification in the presence of two subscribing witnesses.

KATHARINE A. McINTIRE.
